(57) **CLAIM**

The ornamental design for a pedestal, as shown and described.

DESCRIPTION

FIG. 1 is a perspective view of the pedestal of the present invention.

FIG. 2 is a front elevational view of the pedestal of FIG. 1, the rear view being a mirror image.

FIG. 3 is a first side elevational view of the pedestal of FIG. 1.

FIG. 4 is a second side elevational view of the pedestal of FIG. 1; and,

FIG. 5 is a top plan view of the pedestal of FIG. 1. No view of the bottom of the pedestal of the present invention is provided since the bottom of the pedestal, when in use, is not seen.

1 Claim, 3 Drawing Sheets
